FINGER WAVING DEVICE

Lucile Hannon, Memphis, Tenn.

Application September 30, 1946, Serial No. 700,247

4 Claims. (Cl. 132—34)

1

This invention relates to winding devices for accomplishing helical design and particularly relates to devices for curling or winding hair to form mechanically that type of curl or wave known in the hair dressing art as a finger wave.

In normal practice a finger wave is set in wet hair, which upon drying assumes the gracefully curved lines desired. The set, in previous practice, has been accomplished by winding the wet hair about the operator's finger, forming a curl and then pinning the curl in place for drying. This has been a tedious process which has required the expenditure of excessive time.

In other types of curling, the curl or wave is set in the hair by the application of heat and it is highly desirable to provide a mechanical curler which includes heating means for effecting such setting.

Another of the difficulties encountered in hair dressing is the presence of a preexisting curl, either natural or applied, which should be removed in order to properly form the new hair design which is desired. In previous practice this curl removal has been a tedious process requiring much time and patience.

With my new device I have provided means for speedily and accurately forming curls in hair, which may be used to set wet hair or for heat setting of hair and which may be adapted for use in curl removing.

With these problems in view, the objects of this invention are to novelly provide:

A rod or cylinder for winding hair having means for removing the wound hair therefrom without distorting the desired geometrical design of the curl as formed during the removal operation. Preferably the removal means should include means for returning the removal means to normal position.

A rotatable winding rod including an integral internal heating element rotatable therewith, in combination with motor means for mechanically effecting rotation.

Means for removing curls from hair quickly and efficiently, which means are adapted for subsequent mechanical rotation to effect formation of desired curls or waves.

Means for selectively producing either right hand or left hand winding for hair curls.

A motor rotatable hair curling device including

2

means for heating the device in which the motor control and the heat control are independent, whereby rotation may be accomplished, with or without heating, and heating may be accomplished with or without rotation.

A rotatable hair curling device which includes means for receiving standard beauty shop appliances for which rotation is desirable.

As a primary object of the invention, to provide 10 a motor driven hair curling device which includes a clutch combination adapted to disengage the device from its driving source responsive to pull of the hair thereon by which winding of hair is interrupted when the curl has been completed and 15 before the hair of the customer has been so pulled as to cause pain or discomfort.

And in general to improve the design, efficiency and utility of such devices, by providing a small 20 and compact device which is simple and safe in its operation.

The means by which the foregoing and other 25 objects of the invention are accomplished and the manner of their accomplishment will be readily understood from the attached specification upon reference to the accompanying drawings, in which:

Fig. 1 is a side view, partly in section and partly 30 in elevation of the device of this invention, showing the clutch and winding rod arrangement.

Fig. 2 is a longitudinal sectional view of a preferred form of winding rod and a jacket assembly and showing the material removing collar in extended position.

Fig. 3 is a sectional side view of an adapter 35 member for the shaft of the device.

Fig. 3A is an end view of one form of the adapter of Fig. 3, including a cylindrical post portion.

Fig. 3B is an end view of another variation of 40 the adapter showing a square post.

Fig. 3C is an end view of a further variation of the adapter showing a cross or X-shaped post.

Fig. 4 is a view similar to Fig. 1, partly in section 45 and partly in elevation, of a variation of the device of this invention, including a winding rod having a heating element and showing the manner of electrical connection thereto through the rotating shaft.

Fig. 5 is a longitudinal sectional view of a varia-

tion of the winding rod which includes a removable heating element.

Fig. 6 is a sectional view taken on the line VI—VI of Fig. 4.

Fig. 7 is a diagrammatic view of the wiring and circuits of the device.

Fig. 8 is a sectional view taken on the line VIII—VIII of Fig. 4, showing the method of placing the heating elements within the winding rod.

Referring now to the drawings in which the various parts are indicated by numerals:

A casing 11 houses a standard reversible, constant speed, low power electric motor 12. Mounted on casing 11 and secured thereto as by machine screws 14 is a supplemental casing 13 housing a clutch and rotating shaft.

In the construction of the device, it is found preferable to form it with a clutch which is adapted to slip and neutralize the coupling between shaft and motor when the tension on the hair being wound exceeds a predetermined amount, which is that amount of tension which would cause discomfort and pain to the person whose hair is being wound if the pull of the tension is permitted to increase.

In the formation of this slip clutch the armature shaft 15 of the electric motor is preferably so constructed as to include a flat circular friction disc 15a which is preferably integral to the shaft 15 and is turned thereby upon rotation of the shaft. If preferred the disc 15a may be formed separately and integrally secured to the shaft 15 by welding 16.

Mounted on and secured to the disc 15a is a ring 17 having a high coefficient of friction, of which ring the outside radius is substantially equal to the radius of the disc 15a and the inside radius is of such length as to define a friction band, the size of which is sufficient to transmit power of a predetermined amount. It will be seen that the ring 17 has a mean radius r defined by the equation:

$$r = \frac{r_1 - r_2}{2}$$

in which r_1 is the outside radius of the ring and r_2 the inside radius thereof. It will be noted that the band surface of ring 17 may be so varied in order to provide a surface for transmitting whatever amount of power is desired.

Normally in frictional engagement with the ring 17 is a disc 19, preferably of metal, having its dimension substantially equal to the dimensions of the disc 15a and preferably having its surface which engages the ring 17 polished. Preferably integral to the disc 19 is a centrally projecting shaft 19a, extending outward therefrom through and beyond the end of the casing 13, the shaft being preferably journaled in a sleeve bushing 21 anchored in the neck of the casing 13. The shaft 19a is adapted to freely rotate within the bushing 21, and in addition is slidable therewith for the purpose of permitting engagement and disengagement of the clutch discs, in the manner hereinafter described.

The disc clutch engagement is accomplished by a compression spring 23 within the casing 13, one end of the spring 23 bearing against the inner side of the end wall of casing 13 and the other end of the spring bearing against the disc 19 and holding that disc normally in contact with the ring 17, whereby upon rotation of the disc 15a and the ring 17 by the shaft 15, the frictional engagement of the ring 17 with the disc 19 will

effect rotation of the latter disc and the shaft 19a carried thereby.

In order to accomplish the required clutch slip-page effective upon tension on the shaft in excess of the predetermined amount to neutralize the engagement of the clutch members, the strength of spring 23 is of prime importance, and this strength must be such as to hold the disc 19 into frictional engagement with the ring 17 during normal rotation while being able to yield to tension in excess of the predetermined amount. The strength of this spring may then be determined by the equation:

$$F = \frac{63,000H}{(mu),NS}$$

derived from the horsepower equation:

$$H = \frac{(mu),FNS}{63,000}$$

in which equations F is the desired axial force in pounds of the spring 23; H is the horsepower to be transmitted to the shaft 19a through disc 15a, ring 17 and disc 19; (mu) is the coefficient of friction of ring 17 and disc 19; r is the mean radius of the ring 17, as previously determined hereinabove; N is the number of frictional surfaces; S is the speed of the ring 17 in revolutions per minute; and 63,000 is a constant of power transmitted by disc clutches.

The spring 23 abuts the shaft side of the disc 19 and the disc is freely rotatable beneath the spring, although the spring normally holds it against any reciprocable movement toward the end wall of the casing 13 until the pull on the rod exceeds the axial force of the spring, at which time slippage of disc 19 on ring 17 occurs.

At its outer end the shaft 19a is adapted to receive a sleeve and impart a direct drive thereto and may be provided with a recess 24 housing a ball 25, spring loaded by a spring 26, the ball and spring being fitted within the recess so that a minor portion of the ball is projected from the surface of the shaft, the ball being held against further projection as by peening of the upper edges of the recess 24, the spring 26 urging the ball into protrusion from the shaft.

A preferred form of winding rod to be used in this invention consists of a rod having a cylindrical hollow base portion 27 adapted to snugly fit on shaft 19a and having a recess 29 adapted to fit over the protruding ball 25 and effect a snap fit of the base portion on the shaft, preventing accidental removal of the winding rod from the shaft.

The base portion internally terminates in a shoulder 31 adapted to seat on the end of shaft 19a, limiting the movement of the portion onto the shaft. Externally the winding rod is provided with an integral annular flange 33 having a radius substantially larger than the radius of the rod. Anchored to the flange 33 as by anchor clips 34 is a tension spring 35 of sufficient length and strength to permit its extension to the full length of the winding rod without exceeding its elastic limits. Anchored to the opposite end of spring 35, as by similar anchor clips 34, is a collar 37 having an integral sleeve portion 37a. The winding rod consists preferably of a hollow extended cylindrical portion 39 integral with and extending from the base portion 27. The sleeve 37a is adapted to slidably fit the surface of the cylindrical portion 39 and the collar 37 may be slidably moved to the end of the cylindrical portion 39 so as to clear and wipe from the cylindrical portion 39 material or hair which has been

wound thereabout, and, upon release of the collar 37 spring 35 is adapted to return the sleeve and collar to the original position adjacent flange 33.

The outer diameter of the cylindrical portion 39 is equal to the desired inner diameter of the curl or ring to be formed in the hair to be wound, and inasmuch as curls of different size are desirable, the cylindrical portions 39 and their integral base portions 27 are, in the manner pointed out, made removable so that cylindrical portions of desired diameters may be interchangeably used with the device. It will be seen that in Figs. 1 and 2 cylindrical rods of different diameters are illustrated, and it will be understood that the diameter of the cylindrical portion 39 may be varied to provide a cylindrical portion of any desired diameter. Preferably the cylindrical portions are hollow to provide for the optional insertion of additional devices in the manner hereinafter described.

The motor is preferably provided with spring loaded switches 41, one of the switches, as shown in Fig. 7, being adapted to energize the motor for left hand winding and the other of the switches being adapted to energize the motor for right hand winding. These switches are normally spring-held in "off" position so that the switch must be held depressed in order to effect operation of the device. In this manner cut-off of the device may be readily effected by merely removing the finger with which the switch is held depressed.

In the operation of the device, the hair to be curled is secured to a cylindrical portion 39 of desired diameter, by the use of a binder of well known type, or by manually winding a few turns of hair about the portion 39; operation is begun by the depression of the switch 41 selected, and the hair, which has been secured to the cylindrical portion 39, is tightly wound thereabout as a result of the rotation of the winding rod by the motor. As the winding approaches the scalp of the customer the tension on the cylindrical portion 39 increases until it reaches adjacent the scalp, the predetermined amount of tension, which if exceeded would result in a painful pull of the customer's hair. At this point the pull on the cylindrical portion overcomes the tension of spring 23, neutralizing the frictional engagement of clutch disc 19 with ring 17. Cut-off of the motor may then be effected by releasing the switch which has been depressed and the collar 37 moved to the outer end of the cylindrical portion 39, smoothly wiping the wound hair therefrom and compacting it into a ringlet or curl which may then be secured in position by the use of a suitable pin, setting being thereby effected. Upon securing the ringlet in position the collar 37 may be released and returned by the spring 35 to the original position adjacent the flange 33. This winding operation is repeated as many times as is necessary to effect the desired number of curls or ringlets and when curls of differing diameter are desired, cylindrical portions 39 of the desired diameter may be substituted for the cylindrical portion 39 originally in use. It will thus be seen that by the use of this device, curls of the so-called finger curl type may be speedily and accurately formed in a manner hitherto impossible.

In addition there are many standard devices used in beauty parlors which it is desirable to rotate, and for this purpose I have provided an adapter member 43 which is similar in formation to the hollow cylindrical base portion 27 of the winding rod and which includes a recess 29

adapted to fit ball 25 for securing the adapter on the shaft 19a. The adapter is preferably provided with a projecting post portion 45 which may be cylindrical, square, or X-shaped to provide for various fittings of standard implements desired to be used thereon. In use, the adapter is slipped over the end of the shaft 19a and the standard appliance fitted onto the post 45, rotation of the standard appliances being thereafter readily accomplished.

In Fig. 4 a desirable variation of the device is illustrated in which the motor and clutch arrangement shown in Fig. 1 are substantially duplicated. In the device as illustrated in Fig. 4, the winding rod is fabricated with heating coils for effecting heating thereof during rotation, and the shaft on which the winding rod is to be mounted is provided with means for effecting electrical connection to the heating coils to provide energy thereto, even during rotation of the shaft.

As illustrated, brushes 51 are mounted within the casing 13, upon a dielectric element 52, these brushes being in electrical connection with the source of electric power which is utilized for operating the electric motor. Contacting the brushes 51 are rotatable rings 53, 53a which are adapted to supply current through the rotated shaft 55. The rings 53, 53a are mounted on a dielectric ring 57 which is integral with a disc 59, the disc 59 being otherwise similar to the disc 19 illustrated in Fig. 1.

Secured to rings 53, 53a respectively are lead wires 61, 61a which are insulated and are preferably joined together into a cable 63. The cable 63 is extended through the disc 59 and longitudinally within the shaft 55 which is provided with a channel-way 54 to receive the lead wires. The point of entrance through the disc 59 is preferably substantially centrally thereof, but in any event must be within the inner radius of the ring 17. At its outer end shaft 55 is provided preferably with a male fitting 67 to which the lead wires are connected and form an electrical plug thereof. It will be noted that with this assembly a rotatable electrical connection is provided, the disc 59, dielectric ring 57 and rings 53, 53a, together with the lead wires therefrom, rotating as a unit, there being no relative rotation between these parts. The shaft 55 is preferably provided with grooves 69 which are diametrically opposite and lie in the same plane with the electrical plug 67.

Within the casing 13 the spring 23 is segregated from contact with the lead wires and rings by separating collars 71, 71a, one of which is preferably integral with the disc 59 and rotatable therewith and the other of which is preferably mounted on the inner side of the end wall of casing 13. The flow of current into the brushes 51, 51a and therefrom through the lead wires into the electrical plug 67 is preferably controlled by a switch 73, operable independently of the switch 41 and adapted to energize the plug 67 whether the electric motor is in operation or not.

The preferred form of winding rod to be used with this variation of the device includes a hollow cylindrical base portion 75, preferably of plastic, which snugly fits the shaft 55 and has secured therewithin a spring clip 77 which is adapted to engage one of the grooves 69 on the shaft 55 so that the winding rod is keyed thereby to the shaft for use. The winding rod is provided with an integral flange 33, a tension spring 35 and collar 37 and sleeve portion 37a in manner similar

to that heretofore described for the winding rod. The winding rod includes internal resistance wires 79 which are preferably molded within the plastic rod, which is formed as a cylindrical portion 81.

In the form illustrated in Fig. 4, the cylindrical portion 81 is longitudinally slotted as by slot 83, the slot 83 being adapted to have a lock of hair inserted therewithin, this slot being adapted for use in the removal of curls from the hair. Within the base portion 75 the winding rod is provided with contact posts 85 positioned in the same plane as spring clip 77 so that upon keying of spring 77 into one of grooves 69 electrical contact between the electrical plug 67 and the contact posts 85 is insured. The winding rod, including the slot 83, is particularly adapted for the removal of curls from a lock of hair inserted therein, in which operation the heating elements 79 are energized by the moving of switch 73 to "on" position, the connection thereto being effected through the electrical plug 67 and contact posts 85. The heated winding rod is then moved along the lock of hair inserted in the slot, effecting thereby a smoothing action which, in cooperation with the heat, will remove undesired curls from the lock of hair.

In Fig. 5, a further variation of the winding rod is shown which includes the cylindrical portion 39 and a hollow base portion 27 with a spring clip 77 substituted for the ball and spring 25, 26, shown in Fig. 1. It will, therefore, be understood that the shaft 19a of Fig. 1 may be formed, as is shaft 55, with grooves 68 adapted to receive the spring clip 77. In addition, in Fig. 5 a removable heating element is shown inserted therein, this heating element comprising a plug 93 of dielectric material adapted to slidably fit within the hollow cylindrical portion 39 and having internal resistance wires 95 embedded therein, these wires terminating in contact posts 97 similar to the contact posts 85 hereinabove described. It will be seen that by the use of this removable heating plug a winding rod of the type illustrated in Figs. 1 and 2 may be converted to a heatable winding rod adapted for use with the device as illustrated in Fig. 4.

It will be understood that the winding rods may be provided with either form of spring shown and that the rotatable shafts may be formed with a clip receiving groove or with a spring loaded ball as desired.

In operation of the device for heat setting of the hair, the hair is secured to cylindrical member 39 in manner similar to that heretofore described. Heating elements 93 are energized by moving switch 73 to "on" position completing the circuit to the source of power. Motor switch 41 is depressed, effecting rotation and winding of the hair as heretofore described, the hair being heated by the heat from the heating elements, as winding is effected, and the curl imparted thereby to the hair. When the curl has been heat set, the wound hair may then be wiped from the cylinder by collar 37, the wiping action compacting the hair into ringlet form in which it may be pinned in position on the customer's head.

I claim:

1. A device for curling hair, comprising a motor, a shaft coupled to said motor and adapted for hair winding rotation thereby, and a winding rod assembly removably secured to said shaft and rotatable thereby to effect winding of said hair thereabout, said assembly including an elongated finger-like cylindrical member adapted to receive

said hair for winding, an annular collar snugly fitted on said cylindrical member adjacent the base thereof, said collar being slidable along said member in wiping contact with the surface thereof, and means resisting sliding movement of said collar to hold said collar adjacent said member base during rotation of said member, said wiping contact being adapted to compact hair wound on said member for removal therefrom in ringlet form.

2. A device for curling hair, comprising a motor, a rotatable shaft, a slip clutch coupling said shaft to said motor for hair winding rotation thereby and a winding rod assembly removably secured to said shaft and rotatable thereby to effect winding of said hair thereabout, said assembly including an elongated finger-like cylindrical member adapted to receive said hair for winding, slippage of said clutch being effected by tension on said member in excess of hair winding tension, an annular collar snugly fitted on said cylindrical member adjacent the base thereof, said collar being slidable along said member in wiping contact with the surface thereof, and means resisting sliding movement of said collar to hold said collar adjacent said member base during rotation of said member, said wiping contact being adapted to compact hair wound on said member for removal therefrom in ringlet form.

3. A device for curling hair, comprising a casing, a motor in said casing, means for connecting said motor to a source of electrical power, a shaft coupled to said motor for rotation thereby, rotatable electrical means carried by said shaft adapted for connection with said source of power, and a winding rod assembly removably secured to said shaft and rotatable thereby to effect winding of said hair thereabout, said assembly including an elongated finger-like cylindrical member adapted to receive said hair for winding, a heating unit removably inserted within said cylindrical member electrically contacting said shaft-carried electrical means for energizing of said unit by said source of power to heat said cylindrical member, an annular collar snugly fitted on said cylindrical member adjacent the base thereof, said collar being slidable along said member in wiping contact with the surface thereof, means resisting sliding movement of said collar to hold said collar adjacent said member base during rotation of said member, said wiping contact being adapted to compact hair wound on said member for removal therefrom in ringlet form, and switch means mounted on said casing for controlling said electrical connections.

4. A device for curling hair, comprising a casing, a motor in said casing, means for connecting said motor to a source of electrical power, a shaft coupled to said motor for rotation thereby, electrical means carried by said shaft and rotatable therewith, adapted for connection with said source of power, and a winding rod assembly removably secured to said shaft and rotatable thereby to effect winding of said hair thereabout, said assembly including an elongated finger-like cylindrical member adapted to receive said hair for winding, a heating unit within said cylindrical member electrically contacting said shaft-carried electrical means for energizing of said unit by said source of power to heat said cylindrical member, an annular collar snugly fitted on said cylindrical member adjacent the base thereof, said collar being slidable along said member in wiping contact with the surface thereof, means resisting sliding movement of said collar to hold said collar

adjacent said member base during rotation of said member, said wiping contact being adapted to compact hair wound on said member for removal therefrom in ringlet form, and switch means mounted on said casing for controlling said electrical connections.
